UNITED STATES PATENT OFFICE.

JESSE BOYER, OF MASSILLON, OHIO, ASSIGNOR OF ONE-THIRD TO HARMON DRAGE, OF MASSILLON, OHIO.

DIRECTION-SIGNAL.

1,268,673.

Specification of Letters Patent. Patented June 4, 1918.

Application filed June 1, 1917. Serial No. 172,318.

To all whom it may concern:

Be it known that I, JESSE BOYER, a citizen of the United States, residing at Massillon, in the county of Stark and State of Ohio, have invented new and useful Improvements in Direction-Signals, of which the following is a specification.

This invention comprehends the provision of a foot operated signal designed for use 10 in connection with automobiles, and embodies among other features a swingingly mounted arm normally disposed in an inactive position, but capable of readily assuming an active position to indicate to other 15 motorists and pedestrians the course the machine is about to take, this being especially true when turning corners.

The invention is characterized by the provision of an electric lamp carried by the arm 20 to render the latter visible at night, the lamp being energized simultaneously with the movement of the arm to active position, the construction being such as to permit the arm to be actuated during the day without 25 energizing the lamp, when its use is not desired.

The nature and advantages of the invention will be better understood when the following detail description is read in connection with the accompanying drawing, the 30 invention residing in the construction, combination and arrangement of parts as claimed.

In the drawing forming part of this specification like numerals of reference indicate 35 similar parts in the several views and wherein:

Figure 1 is a transverse sectional view 40 through an automobile looking in the direction of the front of the car, and showing the inactive position of the arm.

Fig. 2 is a similar view showing the active 45 position of the arm.

Fig. 3 is an enlarged detail view of the 50 arm.

Fig. 4 is a fragmentary detail view showing 55 the operating cable separated from the switch.

Referring more particularly to the drawings in detail A indicates the floor of the car, 60 and B the wind shield standards.

Secured to each of the standards B is a 65 bracket 10 which may be of any suitable construction and design, and upon which is 55 pivotally mounted a signal arm 11. There

may be one of such arms employed, but if desired these arms may be mounted on both of the standards. The arm 11 normally depends from the bracket 10 and is arranged vertically in an inactive position, but is 60 adapted to assume a horizontal active position, to indicate the course the machine is about to take. Either arm is operated to indicate which way the machine is about to 65 turn.

The means for operating each arm embodies a shaft 12 which extends transversely of the floor A of the car, and journaled in suitable bearings 13 which support the shaft in spaced relation to the floor of the car as 70 shown. If two of the arms 11 are used, the shafts 12 of the respective arms are disposed in axial alinement transversely of the floor of the car as clearly shown in the drawing. The outer extremity of each shaft 12 is 75 formed with spaced collars, and secured to the shaft between these collars is one terminal of a flexible element 15, the opposite end of the element being trained over the enlarged end 16 of the arm within a groove 17, 80 and fixed to the arm at a point below the pivot thereof. The flexible element is adapted to be wound about the shaft 12 when the latter is rotated in one direction, during which operation the arm 11 of the respective 85 shaft is elevated to its horizontal active position. The shaft may be rotated in any suitable manner, but the innermost end of the shaft has mounted thereon a foot pedal 18, 90 normally disposed so that when pressure is 95 exerted against the pedal the shaft will be rotated forwardly to elevate the arm to an active position as above stated. With the shafts disposed in axial alinement the pedals 18 are arranged in juxtaposition approximately at the center of the floor board, in convenient reach of the operator, so that either arm 11 can be actuated as the occasion may require. When pressure is removed from the pedal, subsequent to elevating the arm, the latter gravitates to its 100 normal position with a consequent unwinding of the cable from the shaft, thus rotating the latter in a reverse direction and turning the pedal to its normal position.

The outer extremity of the arm 11 carries an electric lamp 19, connected in circuit through the instrumentality of the wires 20, the circuit including a switch 21 which is mounted on a standard 22 rising from the 110

floor A of the car in juxtaposition to the shaft 12. The switch embodies a fixed contact 23 and a movable contact 24, the latter being pivoted for swinging movement toward and away from the fixed contact 23, and further provided with an offset extremity 25. The flexible element 15 at an appropriate point in its length is formed with a loop 26, which is adapted to surround the offset extremity 25 of the movable contact, so that the movable contact is actuated through the instrumentality of the flexible element 15. Normally, when the arm 11 is in its inactive position the flexible element 15 is partly unwound from the shaft 12, and the loop 26 positioned to maintain the movable contact 24 elevated, and out of engagement with the fixed contact 23. However, when the shaft is rotated to wind the flexible element 15 about the shaft 12, with a view of elevating the arm to an active position as above described, the loop 26 moves downwardly, imparting a pivotal movement to the contact 24 so as to bring the latter into engagement with the fixed contact 23, thus closing the circuit and energizing the lamp. When the arm gravitates to normal position, the movement of the contact 24 is reversed, and thus moved away from the fixed contact 23 and the circuit opening. The lamp is intended to be energized during the night, so as to render the signal arm visible after dark, and consequently it is essential to provide means whereby the arm can be actuated in the day time without energizing the lamp. With my invention this can be readily accomplished by simply disengaging the loop 26 from the offset extremity 25 of the mov-

able contact, during which time the arm can be operated without influencing the switch. 40 Projecting from one side of the switch are spaced pins 27 constituting a stop, to limit the movement of the switch element in an opposite direction.

While it is believed that from the foregoing description the nature and advantages of the invention will be readily apparent without requiring a more extended explanation, I desire to have it understood that what is herein shown and described is merely illustrative of the preferred embodiment of the invention to which I do not limit myself, and that such changes may be resorted to when desired as fall within the scope of what is claimed. 55

What is claimed is:—

A direction signal for vehicles embodying an arm mounted for vertical swinging movement, a rotatable shaft, an electric lamp carried by the arm and connected in circuit, a 60 switch including a fixed contact and movable contact, said movable contact having an offset extremity, a flexible element having one end connected to the arm and its opposite end to the shaft, means for rotating the shaft 65 to wind the element thereabout and elevate said arm, said element being formed with a loop to surround said offset extremity of the movable contact, whereby the latter is operated to energize the lamp simultaneously 70 with the elevation of said arm, and said loop being separable from said movable contact, to permit the arm to be actuated independently of the switch.

In testimony whereof I affix my signature. 80
JESSE BOYER.
